PAPER CUP

Allan A. Adamson, West New York, N. J.

Application July 1, 1935, Serial No. 29,281

8 Claims. (Cl. 229—21)

The object of the invention is an improved paper cup of the rigid i. e. non-folding, flat-bottomed type, neatly and effectively sealed against leakage and adapted to be formed, with a minimum of simple folding operations, from a one-piece blank, with economy of paper as compared with cups of like capacity now in use. These and other objects and advantages will be apparent from the ensuing description and the accompanying drawings, of which Fig. 1 illustrates one form of blank for the improved cup; Figs. 2 and 3 are perspective views of the cup in process of being formed from such a blank; Fig. 4 is a perspective view of the completed cup; Fig. 5 is a sectional view of three such cups nested together as for service from a dispenser; Fig. 6 shows another form of blank; Figs. 7 and 8 are perspective views of a cup in process of being formed from such a blank and Fig. 9 is a view of the completed cup.

According to my invention the cup bottom is square or substantially so rather than circular, as in the cups commonly used, and in its preferred form the walls rise to a more or less circular top.

The blank for making such a cup is best stamped out of hour-glass shape, as shown in Fig. 1, with the waist portion somewhat wider than the side of the square area 1 which is to form the bottom wall of the cup. The dotted lines comprising the sides of the square are fold lines, as will presently appear. From opposite sides of the square base area extend wings 2 and 3 a distance sufficient to provide the intended height of the cup and each of greater width than the side of the base to provide marginal portions 4 which project laterally beyond the sides of the square. Their outer edges are arcuate. By making the blanks symmetrical, as shown, there is no possibility of their being inserted or attempted to be inserted in the hopper of the cup-making machine other than the right way. Their handling is also facilitated.

At the sides of the waist of the blank and intermediate the pairs of marginal portions 4 certain cuts are made or areas stamped out, with the object of facilitating the folding operations and also providing simple but effective sealing means. These cuts or stamped-out areas serve to convert the surrounding parts of the blank into a plurality of tab portions or foldable sealing extensions of the preferred form illustrated, the extensions bordering the side of the base area being marked 5 and those projecting toward each other from the basal edges of the marginal portions 4 being marked 6. Such extensions merge into one another, as indicated, along dotted lines 7, which are fold lines. The fold lines for extensions 6, marked 8, are at an acute angle with

the sides of the square base area to which extensions 5 are appendant.

In forming the cup from such a blank and as shown in Figs. 2 and 3, the wings are folded up about the sides of the base. The marginal portions of the wings are then brought around along the other two sides of the base and overlapped to complete the cup side walls. At this stage (Fig. 3) extensions 5 will project downwardly, being so folded about the adjacent sides of the base; extensions 6 will likewise project downwardly and by virtue of fold 7 (Fig. 1) will engage extensions 5. Being deeper than extensions 5, extensions 6 will of course overlie and project beyond the former. To complete the cup the two sets of extensions are bent toward one another and upwardly, each set into contact with the cup bottom (Fig. 4).

As will be apparent, the described folding does not require complicated machinery but, on the contrary, can be performed on light and hence fast machines, and the folds are all of such character as to be performed surely and with precision and, in consequence, with a minimum of wastage from improperly formed cups. The operations may be further facilitated by scoring the blank along the fold lines.

The actual sealing of the cups can be performed as desired but the blank just described is so shaped and folded as to permit the use of an adhesive which is required to be applied over a small area and to one side only of the paper, which further facilitates handling the blanks in the cup-forming machine. In the drawings (Figs. 1 and 2) the shaded areas indicate glued surfaces, comprising simply the extensions 6 and a narrow strip along the edges of marginal portions of the wings, or one of them.

When so shaped and glued, the blank effects a double-sealing of the cup bottom when folded up as described. The first sealing occurs when the stage illustrated in Fig. 3 is reached, at which time extensions 5 have already sealed the cup bottom by their adherence to the opposed areas of extensions 6. The second and final sealing occurs when the thus-united extensions are bent upwardly and adhered (i. e. the extensions 6 only) to the cup bottom. Thus, with a minimum of thicknesses of paper, the cup bottom is effectively sealed, and incidentally, reinforced.

While possessing the advantages herein referred to, square-bottomed paper cups of the character described are found to nest so snugly as to tend to resist separation by some of the simple forms of cup dispensing apparatus with which such cups could otherwise be used. As is well known, a like though lesser tendency is exhibited by the common smooth-walled frustoconical type of paper cup but the same is or may

be obviated in such cups by setting the bottom of the cup (which is a separate piece) a short distance above the base of the cup walls so that when such cups are nested the walls are not in close adhering contact.

The cup of this invention, however, lends itself readily to another and more simple method of treatment in this regard, which consists in indenting say two opposite side walls (or all four of them if desired) near the cup bottom so as to form steps upon which any like cup inserted into the same will rest. In Fig. 4 such a construction is illustrated, the reference characters 9 indicating such a step or shoulder formed on all four sides of the cup and extending entirely across the cup wall, which is preferred, and in Fig. 5 are shown three nested cups embodying this construction. As will be observed, the bottom of cup 10 rests on the steps 9 of cup 11 with the result that the cup walls are slightly spaced and hence no difficulty whatsoever is experienced in separating them.

Figs. 4 and 5 also illustrate a simple and preferred method of finishing the tops of the cups if not desired to be left as shown in Fig. 3. It consists in flaring the rim somewhat, as at 12, which shape has been found to be convenient and to engage the lips of the user without discomfort. It will be understood, of course, that the edge or rim may be rolled if desired.

Referring now to the form of the invention illustrated in Figs. 6-9, it will be observed that the blank is of the same general configuration and that the same general plan of construction obtains.

This blank differs, however, from that already described in respect to the sealing tabs. In this case the larger, triangular extensions, marked 13, are appended to opposite sides of the square base area 1, and the narrower extensions, marked 14, project from the basal edges of the marginal portions 4 of wings 2 and 3.

While presenting the advantages above alluded to, this form of blank contemplates a somewhat different method of folding. As illustrated in Figs. 7 and 8, extensions 14 are folded down on top of extensions 13 when the wings are bent up and brought together, and, in the next step (Fig. 9) the exposed glued tips of extensions 13 are bent upwardly into engagement with the side walls of the cup. Particularly when using heavy weight papers, as for large size cups, it has been found desirable to shorten extensions 14 so that they terminate as along the line 15. In the result, the preliminary seal will close the corners only of the cup bottom but the advantage is secured that instead of five only three thicknesses of paper occur when extensions 13 are bent up and adhered to the cup sides.

In Fig. 9 the finished cup is shown with the same flared top as in Figs. 4 and 5 and with similar indentations 9 adapting the cup for more convenient dispenser service. In this instance, however, the indentations are provided only on two opposite side walls of the cup.

I claim:

1. A paper cup blank consisting of a substantially square area of a size appropriate for the cup bottom, wings extending one from each of two opposite sides of said area a distance sufficient to provide the intended height of the cup and each of sufficiently greater width than the

side of said area to provide marginal portions projecting laterally beyond the sides of said area far enough to cause the edges of one wing to overlap the edges of the other when said wings are bent up and their said marginal portions brought together to form the cup sides, and foldable sealing extensions on the basal edges of said marginal portions and also on the other two sides of said substantially square area.

2. A paper cup blank of approximately hour-glass shape and having a portion stamped out at each side of the waist thereof of such shape as to form a plurality of foldable sealing extensions on each side, two of which are of triangular form and adapted to be folded about their bases to bring their apices into immediate sealing contact with an adjacent cup wall.

3. A paper cup blank of approximately hour-glass shape and cut at each side of the waist thereof so as to convert each immediately adjacent portion of the blank into three foldable sealing extensions, one of which is adapted to be folded to engage the other two.

4. A paper cup blank comprising a square area dimensioned appropriately to form the bottom of the cup and having wings projecting from two opposite sides of the square a distance equal to the height of the cup and each of a width sufficiently greater than a side of the square to cause said wings to overlap for sealing when bent up and brought together to form the cup sides, and foldable sealing extensions on said wings and on the other two sides of said square area, intermediate and separate from said wings.

5. A paper cup blank consisting of a substantially square area of a size appropriate for the cup bottom, wings extending one from each of two opposite sides of said area a distance sufficient to provide the intended height of the cup and each of sufficiently greater width than the side of said area to provide marginal portions projecting laterally beyond the sides of said area far enough to cause the edges of one wing to overlap the edges of the other when said wings are bent up and their said marginal portions brought together to form the cup sides, portions being stamped out at each side of the waist of the blank to form a plurality of foldable sealing tabs adapted to be folded into immediate contact with cup walls and also foldable sealing areas adjacent each corner of the base area and merging into said tabs.

6. A rigid paper cup adapted to be nested with other like cups and formed from a blank of approximately hour-glass shape, with portions cut out at each side of the waist thereof, and folded to produce a substantially square bottom, two opposite sides of the cup adjacent said bottom being indented to form steps on the inside of the cup, for the purpose described.

7. A paper cup blank of approximately hour-glass shape having portions cut out at the sides of the waist thereof, the areas immediately adjacent said cut-out portions forming a plurality of foldable sealing extensions.

8. A one-piece, rigid paper cup having cup walls and a square bottom wall, foldable sealing extensions on two opposite edges of such bottom wall and on adjacent cup walls, certain of said extensions on each side of said cup being glued to each other and to a wall of the cup.

ALLAN A. ADAMSON.
